UNITED STATES PATENT OFFICE.

CHARLES F. HUMPHREYS, OF LANCASTER, PENNSYLVANIA, ASSIGNOR TO ARMSTRONG CORK COMPANY, OF PITTSBURGH, PENNSYLVANIA, A CORPORATION OF PENNSYLVANIA.

DESIGN FOR A RUG.

Application filed January 23, 1925. Serial No. 12,123. Term of patent 7 years.

To all whom it may concern:

Be it known that I, CHARLES F. HUMPHREYS, a citizen of the United States, and resident of Lancaster, in the county of Lancaster and State of Pennsylvania, have invented a new, original, and ornamental Design for a Rug, of which the following is a specification, reference being had to the accompanying drawings, forming part hereof.

The figure is a plan view of a piece of a rug, showing my new design. The drawing shows the lower left hand corner of the rug, it being understood that the representative illustration is repeated throughout the extent or size of the rug.

I claim:

The ornamental design for a rug, as shown.

In witness whereof, I have hereunto set my hand.

CHARLES F. HUMPHREYS.
